Primary Examiner — Mary Ann Calabrese(74) *Attorney, Agent, or Firm* — Stetina Brunda Garred and Brucker(57) **CLAIM**

The ornamental design for a table, as shown and described.

DESCRIPTION

FIG. 1 is a front perspective view of the table of the present invention showing my new design with the dotted lines depicting environmental structure and forming no part of the claimed design;

FIG. 2 is a top plan view thereof;

FIG. 3 is a front elevational view thereof;

FIG. 4 is a right side elevational view thereof;

FIG. 5 is a bottom plan view thereof;

FIG. 6 is a rear elevational view thereof;

FIG. 7 is a front perspective view of a second embodiment of the table of the present invention showing my new design with the dotted lines depicting environmental structure and forming no part of the claimed design;

FIG. 8 is a top plan view thereof;

FIG. 9 is a front elevational view thereof;

FIG. 10 is a side elevational view thereof;

FIG. 11 is a bottom plan view thereof; and,

FIG. 12 is a rear elevational view thereof.
